UNITED STATES PATENT OFFICE.

EDWIN MEDDEN, OF SENECA FALLS, NEW YORK, ASSIGNOR TO THE
SILSBY MANUFACTURING COMPANY, OF SAME PLACE.

JOURNAL-BOX.

SPECIFICATION forming part of Letters Patent No. 242,672, dated June 7, 1881.

Application filed January 4, 1881. (Model.)

To all whom it may concern:

Be it known that I, EDWIN MEDDEN, a citizen of the United States, residing at Seneca Falls, in the county of Seneca and State of New York, have invented Improvements in Journal-Boxes, of which the following is a specification.

The subject of this invention is a journal-box, or, in its complete form, a connected pair of journal-boxes, consisting of a cast-iron bracket with two cylindrical or nearly cylindrical openings, in which are placed independent thimbles of bronze or other good anti-friction metal, constituting the brasses or bearings of the journals.

The improvement particularly consists in a novel construction of bracket for receiving the thimbles or brasses and securing them in required position; also, in so fitting the thimbles within the sockets of the bracket that they may have a solid bearing within said bracket on the side where the stress and pressure are received while in operation, while on the opposite side, where no pressure occurs, a space is left to permit the expansion of the thimble in event of heating, so that it may not bind on the journal.

In order that my invention and the mode of carrying it into effect may be fully understood, I will proceed to describe it with reference to the accompanying drawings, in which—

Figure 1 is a front view of cast bracket with two boxes and a thimble-bearing applied within one of them. Fig. 2 is a plan of the same. Fig. 3 is a transverse section thereof. Fig. 4 is a plan or side view of one of the thimbles detached. Fig. 5 is a front view of the same.

In the drawings, A represents the outside cast-iron bracket made with two boxes adapted for the reception of thimbles or sleeves B, of bronze or other good anti-friction metal, which constitute the journal bearings or brasses, which are fitted in the said cast-iron brackets or boxes, and at the same time are independent of them. These thimbles or sleeves B constitute journal-bearings for shafts, to which, in rotary engines and pumps, the rotating cams or pistons are attached.

In rotating engines and pumps as heretofore constructed, the metal thimbles or sleeves

B have been made to fit perfectly in the cast-iron brackets or boxes A, for the purpose of keeping the shafts central or in proper place. When the engine or pump or both are running under heavy pressure or at a high rate of speed the thimbles or sleeves B become heated, owing to the excessive friction, and enlarge. The thimbles or sleeves B being tightly fitted in the brackets or boxes A, there is no room for them to expand outwardly, as the natural tendency would be, but they tighten on the shafts and prevent them from revolving, frequently resulting in injury to the machine, and sometimes, in the case of steam fire-engines, indirectly causing the destruction of much valuable property. This difficulty is overcome in my invention by providing sufficient room for the thimbles or sleeves to expand when heated, preventing them from tightening on the shafts, and allowing the latter to revolve freely and perform their full duty. This may be accomplished by relieving or taking off a portion of the thimble or sleeve B—viz., half its circle, or by removing or taking out a portion of the bracket or box A—viz., half its circle; but this should be done on the opposite side from that on which the shaft bears on the journal-box, so that the thimble or sleeve will retain its proper position in the bracket or box and keep the shafts and rotating cams or pistons in their proper places.

I am aware that boxes have before been made with eccentric bushings combined with set-screws for the purpose of adjusting a crank-wrist to its pitman or for analogous purposes; but such a device is inapplicable to my invention, which necessitates the use of a continuous and concentric thimble of cylindrical or nearly cylindrical exterior, fitting concentrically on the journal and fitted within its bracket, so as to leave an extended space on one side, which should extend to one-half the circumference of the thimble, or nearly so. The expansion and contraction of the box are thus automatically compensated for without care or attention on the part of the engineer, and in this respect my invention, especially in its application to steam fire-engines, is practically superior to such as require or admit of variable adjustment in their bearings, and hence

cannot be used by any but skillful engineers without danger of injury or disaster.

Having thus described my invention, the following is what I claim as new therein and desire to secure by Letters Patent:

1. A journal-box for rotary engines and pumps constructed with a cylindrical brass or thimble fitting the journal and supported within a stationary box or bracket, with an extended space on one side between said brass

and its supporting-box, as and for the purposes set forth.

2. The combination of the bracket A and brass or thimble B, constructed and arranged as and for the purposes set forth.

EDWIN MEDDEN.
